(57) **CLAIM**

The ornamental design for a key for panel perimeter clips, as shown and described.

DESCRIPTION

FIG. 1 is a first perspective view of a key for panel perimeter clips that may be used as part of a wall panel system, showing my design in a first embodiment;

FIG. 2 is a second perspective view of a key for panel perimeter clips of FIG. 1;

FIG. 3 is a front plan view thereof.

FIG. 4 is a rear plan view thereof.

FIG. 5 is a top plan view thereof.

FIG. 6 is a bottom plan view thereof.

FIG. 7 is a right side elevation view thereof.

FIG. 8 is a left side elevation view thereof.

FIG. 9 is a first perspective view of a key for panel perimeter clips that may be used as part of a wall panel system, showing my design in a second embodiment;

FIG. 10 is a second perspective view of a key for panel perimeter clips of FIG. 9;

FIG. 11 is a front plan view thereof.

FIG. 12 is a rear plan view thereof.

FIG. 13 is a top plan view thereof.

FIG. 14 is a bottom plan view thereof.

FIG. 15 is a right side elevation view thereof.

FIG. 16 is a left side elevation view thereof.

FIG. 17 is a first perspective view of a key for panel perimeter clips that may be used as part of a wall panel system, showing my design in a third embodiment;

FIG. 18 is a second perspective view of a key for panel perimeter clips of FIG. 9;

FIG. 19 is a front plan view thereof.

FIG. 20 is a rear plan view thereof.

FIG. 21 is a top plan view thereof.

FIG. 22 is a bottom plan view thereof.

FIG. 23 is a right side elevation view thereof; and,

FIG. 24 is a left side elevation view thereof.
